UNITED STATES PATENT OFFICE.

ALBERT FORBES CONANT, OF BOSTON, MASSACHUSETTS.

POCKET MEMORANDUM-BOOK.

SPECIFICATION forming part of Letters Patent No. 404,260, dated May 28, 1889.

Application filed February 25, 1889. Serial No. 301,019. (No model.)

To all whom it may concern:

Be it known that I, ALBERT FORBES CONANT, of Boston, in the county of Suffolk and State of Massachusetts, have invented a new and useful Improvement in Pocket Memorandum-Books, which will, in connection with the accompanying drawings, be hereinafter fully described, and specifically defined in the appended claims.

10 In said drawings, Figure 1 is a side view of my improved memorandum-book, with the binder removed. Fig. 2 is an edge elevation of Fig. 1, but with the binder in place thereon. Fig. 3 shows the book as in Fig. 1, but 15 with the binder in the first stage of its application to the book. Fig. 4 is like Fig. 3, except that it shows the binder at another stage of its application. Fig. 5 shows the last stage of applying the binder. Fig. 6 20 shows the book with the binder in position thereon for use. Figs. 7 and 8 correspond to Figs. 1 and 6, respectively, but show a modification in the book proper, which will be hereinafter fully explained.

25 My present invention is an improvement in certain respects upon that specified in my pending application for a patent, Serial No. 270,698, filed April 14, 1888, for an improvement in pocket memorandum-books; and it 30 consists in the features of novelty hereinafter described in connection with said drawings and specified in the appended claims.

Referring again to said drawings, A represents my improved memorandum-book as a 35 whole, the leaves of writing-paper being shown at *a* and the lids or covers at *b b*. One or both of said lids may, as shown, be cut transversely near the binder and hinged or connected with textile material, *c*, pasted 40 thereto; but such cutting and hinging is not part of my present invention, as it is incorporated in my said previous application.

I cut in the edges of the lids and leaves, near one end, the recesses *d d*, (as also shown 45 in my said former application,) and midway between said recesses and in line therewith I form the slot-like opening *e* through the lids and leaves.

To secure the leaves and lids together as a 50 book, I employ the gum-elastic binder *f*, as in my said former application, and the manner of combining it therewith is as follows, to wit:

One end or bight of the binder is first passed through slot *e*, and is there confined by pressing it against the lid by the thumb of the 55 hand that supports the book, as shown at *g*, Fig. 3. Then the opposite bight or end is by the thumb and finger *h i* of the other hand stretched and carried into the recess *d* at one edge, as shown at the right of the book in 60 said Fig. 3, after which it is carried to the opposite recess, as at the left of the book in Fig. 4, when the bight that had been held by thumb *g* is in like manner stretched and carried first into one and then the other of said 65 recesses, such act being clearly illustrated in Fig. 5. With the binding complete, (that is, when each end or bight of binder *f* has been carried into both recesses,) as is shown in Fig. 6, it is obvious that the binder not only 70 extends from edge to edge of the book on each side thereof, but it passes from each recess *d* round through slot *e* on each side of the book, thereby most effectually securing the lids and leaves together, yet admitting 75 of their being quickly unbound and separated whenever it is desired to replace new leaves for those already filled.

In Figs. 7 and 8 the central slot, *e*, is not, as in the other figures, elongated in the transverse 80 direction of the book, but is formed as an "open slot," so called, it being cut through to the end of the back, as is clearly shown; and while this modification of the slot admits a more ready application of binder *f*, (which 85 when fully in place, as shown in Fig. 2, is in the same position as when the slot is not open,) yet I prefer the form of slot shown in the first six figures of the drawings.

I claim as my invention—

1. As an improvement in memorandum-books, the covers and leaves formed with the recesses across the edges thereof and the intermediate slot, *e*, extending through the book, substantially as specified.

2. In combination with the book formed with the edge recesses and intermediate slot formed therein, as specified, the elastic binder *f*, arranged in said slot and recesses, as specified.

ALBERT FORBES CONANT.

Witnesses:

T. W. PORTER,
EUGENE HUMPHREY.
